[57] CLAIM

The ornamental design for a pillow block bearing hous-
ing, as shown and described.

DESCRIPTION

FIG. 1 is an isometric view of the left side, top and front
of a pillow block bearing housing showing my design;
FIG. 2 is a front view of my pillow block bearing hous-
ing design;

FIG. 3 is a top view of my pillow block bearing housing
design;

FIG. 4 is a rear view of my pillow block bearing hous-
ing design;

FIG. 5 is a bottom view of my pillow block bearing
housing design;

FIG. 6 is a left side view of my pillow block bearing
housing design;

FIG. 7 is a right side view of my pillow block bearing
housing design;

FIG. 8 is an isometric view of the left side, top and front
of an alternate embodiment of my pillow block bearing
housing design;

FIG. 9 is a front view of my alternate pillow block
bearing housing design of FIG. 8; and,

FIG. 10 is a top view of my alternate pillow block
bearing housing design of FIG. 8.
